DISPLAY STAND FOR JEWELRY

Nicholas Barbieri, 88 Freese St., Providence, R.I.

Filed Apr. 6, 1959, Ser. No. 55,357

Term of patent 14 years

(Cl. D80—9)

FIG. I

FIG.2

FIG. 1 is a top perspective view taken from one side and the front of a display stand for jewelry, showing my new design;

FIG. 2 is a rear elevation view thereof; and

FIG. 3 is a vertical sectional view thereof taken along line 3—3 of FIG. 2.

I claim:

The ornamental design for a display stand for jewelry, substantially as shown.
